UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A BACK FOR BRUSHES, MIRRORS, &c.

SPECIFICATION forming part of Design No. 19,702, dated March 18, 1890.

Application filed February 24, 1890. Serial No. 341,624. Term of patent 7 years.

To all whom it may concern:

Be it known that I, HENRY BERRY, a citizen of the United States, residing at Shelton, in the State of Connecticut, have invented and produced a new and original Design for a Back for Brushes, Mirrors, and other Articles, of which the following is a specification, reference being had to the accompanying drawing, forming a part thereof, and which shows a plan view of the mirror-back embodying my design.

The leading features of my design consist in the form or outline of the back and in the surface ornamentation hereinafter described thereon. The leading elements of said surface ornamentation consist in a fluted scroll occupying one side of the said back and gradually diminishing toward the other side thereof, which forms a field bearing a conventionalized foliated scroll, all as hereinafter more particularly described.

In the drawing, A designates the fluted scroll occupying one side of the back, which scroll has the convolved figure B at its base, and gradually diminishes into the field C, which occupies the opposite side of the back and bears the conventionalized foliate scrolls D E, the former being on the upper portion of said field and the latter on the central and lower part thereof, and being evolved from the convolved figure F at the base of the back and corresponding with the figure B. The scroll A and field C, bearing the scrolls, have a well-defined outline, as shown in the drawing, the side edges a b of same curving upward to the highest point d of the scroll, which point is at one side of the vertical line of center of the back. The side edges a b extend upward to the point d, the edge b, instead of passing directly to the point d, swelling outward at e, as shown. Intermediate the convolved figures B F and the handle H

is the base I, wider at its upper end than at its lower end, and ornamented with the line-scrolls J, which follow the general outline of each other and are curved upward at their middle portions. The handle H is novel in its design, but is not sought to be protected hereby, having been made the subject of a separate application of even date and filed here-with, and serially numbered 341,627.

When the design is to be used for brush-backs, I prefer to use the surface defined within the side edges a b alone; but when a more extended surface is desired—such as for mirror-backs—I prefer to inclose the fluted scroll A and field C within the field K, corresponding in general outline with the sides a b and bearing the scalloped ornamentation L, following the line of the edges a b, the scallops gradually reducing in size from the point d downward along said edges and bearing circular figures M, which also are gradually reduced in size as they extend downward along said edges.

In the employment of the design I shall make use of the field K and scalloped ornamentation L, or omit the same, as I may prefer, according to the desired effect to be produced and the extent of the surface of the back.

What I claim as my invention, and desire to secure by Letters Patent, is—

The design for a back for mirrors, brushes, and other articles, substantially as shown and described.

In witness whereof I hereunto affix my signature, at Shelton, Connecticut, this 18th day of February, 1890.

HENRY BERRY.

In presence of—

WESLEY L. CLARK,
JNO. J. HADLOW.
